UNITED STATES PATENT OFFICE

2,146,763

BROAD SWEEP ELECTRIC CLEANER

Daniel Benson Repleglo, Berkeley, Calif., assignor
to The Ohio Citizens Trust Company of Toledo,
Ohio, a corporation of Ohio, as trustee

Application December 27, 1935, Serial No. 56,384

8 Claims. (Cl. 15—14)

The invention relates to cleaning apparatus and more particularly to portable electric apparatus which may be selectively employed for cleaning the walls or floors of a room or the like.

5 One of the features of my invention is the provision of a flexible tube connected with a source of suction and which may be used for wall cleaning purposes with any desired type of suction nozzle, or may be connected to a floor 10 tool so as to produce suction therein for floor cleaning purposes.

Another feature of the invention resides in the provision of extensions for the floor tool which are adapted to rapidly sweep dance floors and 15 the like, and which may be selectively connected to or disconnected from the source of air pressure according as the floor tool is lifted or depressed, and which when disconnected from the source of pressure may remain connected to the tool's suction outlet.

Other features of the invention will be apparent from a consideration of the accompanying drawings in which one embodiment of the invention is set forth by way of illustration.

25 In the drawings:

Fig. 1 is a side elevation of the cleaner, portions being broken away to show the interior of the barrel shaped casing, container or caddy which houses the power plant and the dust collecting 30 and air filtering means;

Fig. 2 is a top plan view on a large scale showing the floor tool and the lower portion of the power plant casing;

Fig. 3 is a side view of the floor tool casting, 35 the end rollers being removed;

Fig. 4 is a plan view of the same;

Fig. 5 is a view similar to Fig. 2 but showing the floor tool equipped with a lateral extension member;

40 Fig. 6 is a perspective view of one of the end rollers which supports the floor tool;

Fig. 7 is a view on line 1—7 of Fig. 6;

Fig. 8 is a view similar to Fig. 5 but showing the floor tool equipped with two extension members;

45 Fig. 9 is a fragmentary view on an enlarged scale showing a portion of the end of one of the floor tool extensions partly broken away to disclose the interior thereof, the parts being in the position which they normally occupy;

50 Fig. 10 is a view similar to Fig. 9 but showing the position of the parts when downward pressure is applied to the floor tool;

55 Fig. 11 is a section on line 11—11 of Fig. 9

showing the roller which supports the end of the extension member;

Fig. 12 is a horizontal section on line 12—12 of Fig. 9;

Fig. 13 is an exploded sectional view showing 5 one of the end extensions and a portion of the floor tool and illustrating the means by which they are attached, certain portions being shown in elevation;

Fig. 14 is a top plan view of the same; and

10

Fig. 15 is an end view.

It will be understood that the drawings are intended as illustrative only of the invention and not as limiting the same to the details herein disclosed.

15 As shown, reference numeral 10 denotes a barrel shaped casing, caddy or container which houses at its lower end a power plant or suction producing means 11 including one or more motors driving one or more fans preferably of the centrifugal type. Electric current is supplied to the power plant through conductor cord 12, and 20 13 denotes an extension switch.

Above the power plant or suction producing 25 means 11 is housed a suitable dust collecting and air filtering device herein shown as including a porous paper bag 14, but it will be understood that the present invention is not limited to any particular type of power plant or any particular form of dust collecting apparatus. The top of 30 the casing 10 is preferably closed by a transparent cap 15 which may be secured to the dust collector bag so as to withdraw the same from its housing. A handle portion 16 which may be of hard fiber or the like is shown connected to the 35 cap and provides means for moving the apparatus about from place to place. Suitably connected to the hollow handle 16 is a flexible hose 17, at the other end of which is connected a hard fiber member 18 which is detachably connected 40 to the floor tool A at 19. If desired, the connection between the handle portion 16 and the flexible tube may be detachable and likewise the connection between the tube 17 and the member 18, or the flexible tube may be directly connected 45 to the floor tool without the intermediate stiff connector 18. If desired, a permanent rotatable joint 25 may be interposed between the flexible pipe 17 and the tube 18, a suitable joint being disclosed in my Patent No. 1,836,336. Also, connections such as are described in my application 50 Serial No. 586,192 may be employed where fluid tight joints between the various extension members are required.

According to the shown embodiment of my 55

invention, the floor tool forms part of a single casting which includes a cap 20 for the lower end of the barrel 10 and is provided with two laterally extending fan exhaust outlets 21, 21, either of which may be capped if desired and the other connected by a hose or otherwise to any location where air under pressure is required. Each outlet 21 is large enough to take the entire output of the fans, so that when either is capped, there is no interference with the free flow of air through the other outlet. The suction nozzle of the floor tool may be of the general type disclosed in my Patent No. 1,994,868, dated March 19, 1935, and is provided with yielding end rollers 22 in accordance with the disclosure of said patent.

10 The body of the cleaner may be supported by one or more rollers 23 carried by the supporting member 24 shown as of twisted flexible metal.

This support is sufficiently rigid to bear the weight of the apparatus.

In operation, the cleaner is pushed back and forth over the floor with the floor tool in floor engaging position. To pass over the edge of a carpet or the like, the apparatus may be tilted about the roller or rollers 23. To clean walls or the like, the flexible tube with the rigid extension member 18 may be separated from the floor tool at the joint 19 and the hose with its extension member may be directed to any suitable location. Owing to the swivelled pipe joint 25, the member 18 may be rotated at an angle about the hose, thus facilitating the cleaning operation. Any suitable nozzle or extension members may be secured at the end of the member 18. Also, if desired, the hose 17 may be removed from the handle 16 and other connectors applied thereto, suitable extension members being shown in my Patent No. 1,533,271, dated April 15, 1925. Any supplemental device 30 such as a wax heater, floor agitating means or the like, actuated by electric means may be connected through the extension member 18.

Wherever as shown, the floor tool is rigid with the barrel member 10, difficulty might be experienced in sweeping under low articles of furniture and to take care of this requirement, extension members B and C may be applied. These extension members are alike and but one need be described. One or both extension members 45 may be applied to the floor tool by simply removing one or both end rollers and applying the corresponding extension, member or members. These extensions may be applied similarly to the roller and for this purpose are provided with 50 spring supports 26 similar to the roller supports disclosed in my Patent No. 1,999,868.

Referring particularly to Figs. 8 and 13, each extension member includes a funnel or the like 60 27 which is adapted to fit within the exhaust outlet 21, while a cap 28 fits tightly over the outside of the outlet, a bayonet connection being adequately employed. Passages and air-ways lead from the exhaust outlet to the interior of the extension. As shown, a passage 29 communicates with the upper half 30 of the extension member which is divided from the lower half by a partition 31 having an air-way 32 therein at the end thereof. This air-way permits air to 65 pass through into the lower half 33, as indicated by the arrows, and thence to the interior of the suction nozzle proper. In this manner, dust is blown from the ends of the extension into the suction nozzle, hence it is drawn into the nozzle 70 itself and passed through the connecting mem-

bers 18 and 17 to the dust collecting and air filtering mechanism.

A flap valve 34 hinged at 35 is provided for closing the air-way 32. When the flap is down, exhaust air from the portion 21 passes out through an air-way 40 at the top of the extension. This air-way is closed by the flap valve 34 when the air-way 32 is placed in communication with the air under pressure.

Means are provided for interchangeably applying the flap 34 according as the floor tool is lifted or depressed. When the floor tool is lifted slightly as by tilting about the roller 23, the flap 34 assumes the position shown in Fig. 9. When the tool is pressed down, the flap assumes the 15 position shown in Fig. 10. As illustrated, a roller 36 is provided at the end of the extension member, this roller being mounted upon a frame or support 37, the tip 38 of which is adapted to engage and actuate the flap 34.

According to the embodiment of the invention herein illustrated, the flap 34 falls by gravity when the floor tool is raised and is shoved to the raised position shown in Fig. 10 when the floor tool is depressed. However, any suitable means 25 may be employed whereby the flap valve is automatically actuated by lifting or depressing the floor tool.

The invention may be varied in detail without departing from the spirit thereof.

I claim:

1. A floor tool including a nozzle adapted to be connected to a source of suction, an end pocket carried by said nozzle; and an end extension having a portion detachably fitting within said end pocket, said end extension being adapted to be connected to a source of air pressure for blowing dust laden air into the range of the suction of the floor tool nozzle.

2. A floor tool adapted to be connected to a source of suction, having an end extension adapted to be connected to a source of air pressure for blowing dust laden air into the range of the suction of the floor tool nozzle, and means for automatically applying or cutting off the air pressure from the extensions as the floor tool is lifted or depressed.

3. As a new article of manufacture, a casting combining a removable cap adapted to cover the discharge end of a casing housing the dust collecting and suction producing means of a portable suction cleaner, with a floor cleaning suction nozzle having an inlet mouth and an outlet for dust laden air, said cap having lateral discharge outlets for air under pressure, connectible with means for blowing air into the range of said nozzle.

4. In a portable suction cleaner, a cylindrical housing having a motor driven fan at one end and air filtering means at the other; a casting 60 combining a cap adapted to cover the discharge end of the housing and having a pair of lateral outlets, with a floor cleaning suction nozzle, having an inlet mouth and an outlet for dust laden air; a detachable flexible tube communicating 65 at one end with the air filtering means of the housing and adapted to be connected at its other end with the discharge outlet of said nozzle, and blowing extensions detachably secured at the ends of the nozzle and arranged to blow dirt end- 70 wise into the mouth of the nozzle, said extensions having air inlets communicating with said lateral fan discharge outlets.

5. A floor tool comprising an elongated nozzle adapted to be connected to a source of suction 75

and having an inlet mouth and an end opening, an extension device adapted to be detachably secured at the end of said nozzle having an air passage communicating with said end opening, and means for supplying air under pressure to said passage for directing dust into said nozzle, the suction nozzle being provided with an end pocket above said end opening, and the extension device being provided with a spring shank detachably fitting in said end pocket.

6. In a portable suction cleaner, a cylindrical body portion housing air filtering means at one end and suction producing means including a motor driven fan at the other, a detachable cap at the fan discharge end of the casing having a pair of laterally directed discharge outlet openings, an elongated suction nozzle formed integral with the cap and having end openings and an outlet for dust laden air, a suction pipe connecting the nozzle outlet with the air filtering end of the cylindrical housing, and end extensions detachably secured to said nozzle for blowing dust laden air thereinto, each extension having a passage communicating at one end with said nozzle and

at the other with one of the discharge outlets of said cap.

7. In a device of the character described, a conduit having an inlet and an outlet, a power unit mounted in the conduit, including a motor and a fan operated thereby, a removable cap at the discharge end of the conduit having a pair of oppositely directed blower openings, a floor tool having a nozzle connected to the inlet of said conduit, and blower extensions detachably secured to the ends of the nozzle and operatively connected to said blower openings, for directing dust laden air into the range of suction of said nozzle.

8. In a suction cleaner, a casting combining a floor cleaning suction nozzle, which is adapted to be used with blower extensions, and a cap formed integral with the nozzle and adapted to cover the discharge end of a casing housing the power plant of the portable suction cleaner, said cap having outlets connectible with said blower extensions.

DANIEL BENSON REPLOGLE.
